UNITED STATES PATENT OFFICE.

FRANK KERBY, OF WOOLLAHRA, NEAR SYDNEY, NEW SOUTH WALES, AUSTRALIA.

MOTOR-CAR AND OTHER DOOR LOCK.

Application filed April 29, 1924. Serial No. 709,829.

To all whom it may concern:

Be it known that I, FRANK KERBY, a subject of the King of Great Britain, residing at Woollahra, near Sydney, in the State 5 of New South Wales, Commonwealth of Australia, have invented certain new and useful Improvements in Motor-Car and Other Door Locks, of which the following is a specification.

10 This invention relates to improvements in motor car and other door locks which I have devised with the view to providing an inexpensive lock of this class which will hold the door securely in the closed position without noise or "play" due to vibration or to wear. The lock is especially applicable to the doors of vehicles.

According to the invention the door is provided with a suitable base plate on or in 20 which is fitted an approximately U shaped spring whose arms are substantially horizontal normally. The free ends of the arms project beyond the closing side of the door at different heights, preferably adjacent the 25 top and bottom of the lock. Between the arms of the springs is a cam block adapted to be rocked on a central pivot by a hand lever or push rod fixed to or integral therewith so as to spread the arms. In the door frame in alignment with the arms in their 30 normal position are keepers provided with inclined faces so that on the door being forcibly closed to, or on the hand lever and cam being moved, the ends of the arms are 35 spread and ride up the inclined faces of the keepers and are retained on the handle being released. A wedge shaped block on the base plate intermediate the spring arms may take into a corresponding recess between the keepers.

40 Preferably the inner faces of the keepers are inclined oppositely so that the arms are held thereon without any possibility of play. To unlock the door, the hand lever is moved so that the cam spreads the arms clear of the keepers whereupon the door 45 can be opened.

The arms may be coupled with a suitable spring to ensure quick return to the horizontal position.

50 But in order that the invention can be clearly understood I will refer to the ac-

companying drawings which illustrate the preferred form of my invention.

Figure 1, is a part perspective view of a 55 door and its frame fitted with the invention, and

Figures 2 and 3 are sectional elevations on line 2—2 Figure 1 of the lock, in the closed and open positions respectively. 60

The same numerals indicate like parts throughout.

6 This is the base plate of the lock, and 7 is the U shaped spring whose arms 8 and 9 are of increased thickness at the ends 10 and 11 respectively. The U shaped spring 7 is anchored to the base at 12, and 13 and 14 are stops to limit the travel of the arms 8 and 9 outwardly. 15 is the cam block pivoted at 16, and operated by a suitable handle 17. 18 is a dovetail shaped block intermediate the ends 10 and 11 and which fits into a corresponding recess 19 in the keeper plate 20. 21 and 22 are the keepers with inclined faces 23 and 24 respectively, whereby the ends 10 and 11 of the U shaped spring are forced outwardly and so spring into the keepers to lock the door. The inner faces of these keepers are also inclined at 26 and 27 to conform to the shape or section of the ends 10 and 11 thereby allowing these ends to properly seat in the keepers to prevent vibration. A spring 25 may be secured to the cam block 15 to assist in returning the handle 17 to its normal position. 70

75 Doors fitted with this improved lock are prevented from vibrating as the spring arms 8 and 9 rigidly hold their ends 10 and 11 in close contact inside the keepers. The dovetail block 18 also prevents any side play in the lock and takes up any wear or sag of the door due to the dropping of the hinges. 80

85 It is obvious that instead of one U spring, two spring arms separately anchored on the base plate may be employed.

I claim:

90 A vehicle door lock comprising a casing having spaced slots in the front end thereof, and also having a wedge shaped block on the front end between said slots, a U shaped spring having its right portion secured 100 within the casing, and its arms extending

through and movable laterally in said slots, the arms of the U shaped spring being wedge shaped, a striking plate on the door jamb, said plate having wedge shaped keepers, to receive the wedge shaped block, and means to spread the arms of the U shaped spring to unlock the door. ¹⁰
5. keepers to receive the wedge shaped ends of the U spring, and also having a wedge shaped recess between said wedge shaped

In testimony whereof I have hereunto set my hand.

FRANK KERBY.
